UNITED STATES PATENT OFFICE.

WALTER THOMAS, OF BARRY, WALES.

DESIGN FOR A COMBINED KNIFE AND FORK.

60,589.

Specification for Design.

Patented Mar. 7, 1922.

Application filed May 9, 1921. Serial No. 468,176. Term of patent 7 years.

● (GRANTED UNDER THE PROVISIONS OF THE ACT OF MARCH 3, 1921, 41 STAT. L., 1313.)

To all whom it may concern:

Be it known that I, WALTER THOMAS, a subject of the King of Great Britain, residing at 23 Bendrick Road, Barry, in the county of Glamorganshire, in Wales, have invented a new, original, and ornamental Design for a Combined Knife and Fork, of which the following is a specification, for which I filed an application in England September 13, 1920, reference being had to the accompanying drawing, forming part thereof.

Fig. 1, is a side elevation, and Fig. 2, is an edge view, showing my new design.

I claim:

The ornamental design for a combined knife and fork, as shown.

WALTER THOMAS.
